UNITED STATES PATENT OFFICE.

MICHAEL E. REILLY, OF TACOMA, WASHINGTON.

WINDOW-SHADE.

SPECIFICATION forming part of Letters Patent No. 733,996, dated July 21, 1903.

Application filed April 28, 1903. Serial No. 154,668. (No model.)

To all whom it may concern:

Be it known that I, MICHAEL E. REILLY, a citizen of the United States, residing at Tacoma, in the county of Pierce and State of Washington, have invented a new and useful Window-Shade, of which the following is a specification.

My invention relates to window-shades which are divided into sections, and more particularly is an improvement of my Patent No. 715,294, issued December 9, 1902, and has for its object the reduction of the shaded area when the curtain is in its closed or contracted position. I attain this object by the device illustrated in the accompanying drawings, in which—

Figure 1 is a front view of a window equipped with my shade, showing the shade extended to cover the window. Fig. 2 is a similar view showing the shade contracted or closed and lowered slightly from the top to shade only a certain portion of the window. Fig. 3 is a detail of the link. Fig. 4 is a perspective view of the shade in its closed position, the parts thereof being separated for greater clearness. Fig. 5 is a detail of a modified form of hanging my shade.

Similar letters of reference refer to similar parts throughout the several views.

My improved shade consists of three similar parts, (marked, respectively, A, B, and C.) The parts A and C are connected by the cord D, passing through the loop E of the link-piece F. The length of the cord D is practically twice the vertical length of either of the parts A or C. The part B, of substantially the same dimensions as the parts A and C, hangs between the parts A and C by the cord G. This cord is about one-half as long as the cord D, and I prefer to attach its upper end to the loop H of the link F. It will be seen that the part B does not move relatively to the link F, but moves with it when that link is moved. It will be also understood that between the link F and the upper edge of B is an open space substantially as long vertically as the part B. This open space is closed by either the part A or C when the shade is extended to cover the window.

The link F, I prefer to construct with two loops E and H. The lower loop E sustains the cord D, holding the parts A and C, but

allows the cord free motion through it. The upper loop H has the cord G fastened to it, as well as the main cord I, which holds the entire curtain. The cord I passes through the hanger J, secured to the window-casing, the hanger K, secured near the upper corner of the casing, and down the side of the casing through a keeper L, to which it may be secured. Keeper L may be placed in any convenient position. Hanger J must be large enough to allow the link F to pass through it freely.

In Fig. 5 the hanging arrangements are practically duplicated, one being at each end of the shade parts A, B, and C. The hangers J are placed over each end of the curtain instead of a single one over the center, and the cords I pass together through the hanger K and the keeper L and may be fastened together at any suitable point.

My improved shade, it will thus be seen, need shade only one-third of the window area when drawn up, whereas my former curtain always shaded at least one-half thereof. The whole shade when contracted or closed, as in Fig. 2, may be placed to cover any portion of the window by raising or lowering the link F by means of the cord I.

What I claim, and desire to secure by Letters Patent, is—

1. In a sectional window-shade, the combination with a cord for raising and lowering all the sections thereof together, of a link secured to said cord, of a hanging cord secured to said link, of a section of said shade immovably secured to said link by means of said hanging cord, of a pair of sections of said shade, and of a movable cord passing freely through said link and having one of said pair of sections at each end whereby said sections are adjustably and complementarily supported by said link.

2. A sectional shade composed of a section immovably hung from a link and a pair of vertically-slidable sections adjustably and complementarily hung from said link.

3. A sectional shade composed of a section immovably hung from a link at a distance therefrom of substantially the vertical length of said section, and a pair of vertically-slidable sections hung from said link at the ends of a cord of substantially twice the vertical length of said section.

4. A sectional window-shade composed of three sections each of a vertical length substantially one-third of the vertical length of the window, means for raising and lowering said sections, together and means for vertically sliding the members of one pair of said sections respectively above and below the third section.

In testimony whereof I have signed my name to this specification in the presence of two subscribing witnesses.

MICHAEL E. REILLY.
